ELECTRIC IRON

Filed April 28, 1930

UNITED STATES PATENT OFFICE

FRANK KUHN, OF DETROIT, AND LAURENCE H. THOMAS, OF BIRMINGHAM, MICHIGAN,
ASSIGNORS TO AMERICAN ELECTRICAL HEATER COMPANY, OF DETROIT, MICHIGAN,
A CORPORATION OF MICHIGAN

ELECTRIC IRON

Application filed April 28, 1930. Serial No. 448,099.

This invention relates generally to electric heaters and more particularly to thermostatically controlled electric irons and has as one of its objects to cheapen the cost of manufacture and facilitate assembly by simplifying the construction of the several parts involved and by reducing the number of such parts to a minimum.

The invention provides for simplifying the construction and facilitating assembly by introducing improved means for supporting a thermostatic switch assembly within the heater permitting the switch assembly to be readily removed from and assembled with the heater as a unit.

With the above as well as other objects in view, the invention resides in the novel details of construction which will be made more apparent as this description proceeds, especially when considered in connection with the accompanying drawing, wherein:

Figure 1 is a fragmentary sectional view through an electric iron constructed in accordance with this invention.

Figure 2 is a fragmentary top plan view of the construction shown in Figure 1 with certain parts broken away for the sake of clearness.

Figure 3 is an end elevational view of the construction shown in Figure 2.

Figure 4 is a sectional view taken on the line 4-4 of Figure 2.

Referring now to the drawing, it will be noted that there is illustrated in Figure 1 an electric iron 10 comprising a heating element 11 clamped between the pressure plate 13 and the heat distributing base plate 14 by means of the fastener elements 15 having the head portions thereof engaging the top surface 16 of the pressure plate and having the shank portions extending through suitable aligned openings in the latter plate and heating element and threadedly engaging the base plate 14. The above parts of the iron are preferably inclosed by a suitable cover or hood 17 seated upon the base plate 14 and having the conventional handle secured thereto in any suitable manner.

For controlling the operation of the heating element, we provide a switch unit design-

nated generally by the reference character 19 and comprising a bracket 20 arranged within an elongated opening 21 formed in the pressure plate 13 and having a portion 22 for supporting a pair of cooperating thermostatic strips 23 and 24 in close proximity to the heat distributing plate 14 of the iron so as to receive heat mainly therefrom. As shown in Figure 1, the strips 23 and 24 are disposed within a recess 25 formed in the base plate and are arranged in superposed relation. The fixed ends of the strips 23 and 24 are secured to the portion 22 of the bracket 20 by means of a fastener element 26 which also serves to secure the terminal members 27 and 28 to the strips 23 and 24, respectively. As shown in Figure 3, the terminal 28 is electrically connected to one end of the heating coil forming the heating element, while the terminal 27 is electrically connected to a source of electric energy in a manner to be presently described. The construction is such that the thermostatic strips 23 and 24 are connected in series with the circuit to the heating element for controlling the operation thereof.

The bracket 20 is provided with another portion 29 spaced above the portion 22 and adapted to project beyond the same as clearly illustrated in Figure 1. The portion 29 of the bracket is provided with a threaded opening 30 therein adjacent the free end thereof for adjustably receiving a sleeve 31. The sleeve 31 is provided with an internally threaded bore for adjustably receiving a regulating element 32. The lower portion of the regulating element 32 is provided with an enlarged head 33 arranged in the path of travel of a projection 34 extending upwardly from the lowermost thermostatic strip 24 adjacent the free end thereof. The arrangement is such that when the iron reaches a certain predetermined temperature, the free ends of the strips 23 and 24 are moved upwardly under the influence of the heat until the projection 34 engages the head 33 at which time further upward movement of the strip 24 is prevented. As the temperature continues to rise the upper strip 23 moves away from the strip 24 breaking the electrical

connection therebetween and since the thermostatic strips are connected in the circuit to the heating element, the flow of current to the latter is discontinued. The temperature at which the head portion 33 is adapted to engage the projection 34 to arrest upward movement of the strip 24 may be varied by adjusting the regulating member 32 within the sleeve 31. The above adjustment may be accomplished from a point exteriorly of the iron since the regulating member 32 projects through the hood 17 and detachably engages a suitable operating member 35. The extent of adjustment of the regulating member 32 is limited by a stop 36 projecting laterally from the head portion 33 in the path of travel of a fixed stop 37 depending from a flexible strip 38 intermediate the ends of the latter. One end of the strip 38 is secured to the under surface of a portion 29 of the bracket by means of a fastener element 40 while the opposite end of the flexible member is adapted to engage the head portion 33 to compensate for any back lash between the threads of the regulating member 32 and the sleeve 31. As set forth above, the sleeve 31 is threadedly mounted upon the portion 29 of the bracket so as to be capable of axial adjustment. By virtue of this latter arrangement, the initial position of the regulating member may be accurately determined so as to give the desired range of adjustment. This adjustment may be accomplished from without the iron by merely detaching the control lever 35 and inserting a suitable tool through the opening 35' to engage the tool engaging portions 36' of the sleeve 31.

In order to rigidly support the bracket 20 within the recess 21 in the pressure plate, we provide a plate 41 seated upon the top surface 16 of the pressure plate and detachably secured thereto by means of the fastener elements 15, hereinbefore discussed. The plate 41 is rigidly secured to the portion 29 of the bracket by means of the fastener element 40, above referred to, which, as shown in Figure 1, extends through a suitable aperture in the hood 17 for engagement by the nut 42. The construction is such that the fastener element 40, in addition to securing the plate and flexible member to the bracket to form a unitary construction therewith, also functions to detachably secure the cover in assembled relation upon the heat distributing base plate 14 of the iron.

For connecting the heating element and switch to a source of electrical energy, we provide a pair of terminal members 43 and 44 having portions secured to the plate 41 by means of the fastener elements 45 and 46 and having other portions extending upwardly from the plate through the hood portion of the iron for engagement with the conventional electric plug or the like. The terminal 43

is electrically connected by means of the conductor 47 to the terminal 27 for the thermostatic strip 23, while the terminal 44 is electrically connected to the free end of the heating coil, the opposite end of which being connected to the terminal 28 as pointed out above. The arrangement is such as to establish a circuit from the supply of electrical energy through the heating element and thermostatic strips 23 and 24.

Thus, from the foregoing it will be observed that we have provided a mounting for a switch unit upon an electric iron in the form of the plate 41 which serves to secure the thermostatic strips, terminals for the strips, means for regulating the operation of the thermostatic strips, means for holding the cover in assembled relation upon the heater and the main terminal members for the heating element together as a unit. It will further be observed that we have provided a mounting of the type specified above adapted to be secured in assembled relation with the iron by the fastener elements for clamping various parts of the iron together which not only tends to facilitate assembly but contributes to economical manufacture.

What we claim as our invention is:

1. A switch assembly for an electric iron having a base plate, a pressure plate and a heating element, said assembly comprising thermostatic members for controlling the operation of the heating element, a bracket having a portion supporting the members aforesaid in close proximity to the base plate of the iron so as to receive heat mainly therefrom and having another portion extending upwardly through an opening in the pressure plate of the iron, a member supported on the pressure plate and secured to said bracket for supporting the latter in position within the iron, and terminal members carried by said latter member and extending upwardly therefrom for electrically connecting said heating element and switch to a source of electric energy.

2. A switch assembly for an electric iron having a base plate, a pressure plate and a heating element, said assembly comprising thermostatic members for controlling the operation of the heating element, a bracket having a portion supporting the members in close proximity to the base plate of the iron so as to receive heat mainly therefrom and having another portion projecting upwardly through an opening in the pressure plate of the iron, a member seated upon the top surface of the pressure plate and secured to said bracket for supporting the latter in position within the iron, regulating means carried by said bracket and operable to control the temperature at which said thermostatic members are adapted to operate, means for electrically connecting the heating element and switch to a source of electric energy in-

cluding terminal members secured to said last-mentioned member.

3. A switch assembly for an electric iron having a base plate, a pressure plate and a heating element, said assembly comprising 5 thermostatic members for controlling the operation of the heating element, a bracket having a portion supporting the thermostatic members in close proximity to the base plate 10 of the iron so as to receive heat mainly therefrom and having another portion projecting upwardly through an opening in the pressure plate of the iron, a plate seated upon the top surface of the pressure plate and detachably secured thereto, means for securing the plate to the bracket forming a unitary construction therewith and terminal members secured to said plate and electrically connected to the heating element and switch.

20 4. A switch assembly for an electric iron having a cover, a base plate, a pressure plate and a heating element, said assembly comprising 25 thermostatic members for controlling the operation of the heating element, a bracket arranged within a recess in the pressure plate of the iron and having a portion for supporting the thermostatic members in close proximity to the base plate of the iron so as to receive heat mainly therefrom, a plate 30 seated upon the top surface of the pressure plate and detachably secured thereto, means for securing both the plate to the bracket and the cover for the iron in assembled relation with the latter and terminal members carried by the plate and extending upwardly 35 therefrom through the cover for the iron.

5. A switch assembly for an electric iron having a cover, a base plate, a pressure plate and a heating element, said assembly comprising 40 thermostatic members for controlling the operation of the heating element, a bracket for supporting the member in close proximity to the base plate of the iron so as to receive heat mainly therefrom, a plate seated 45 upon the top surface of the pressure plate and detachably secured thereto, means carried by said plate for securing the latter to the bracket to form a unitary construction therewith and for detachably securing the 50 cover for the iron in assembled relation with the latter, and terminal members secured to said plate and electrically connected to the heating element and thermostatic switch.

6. A switch assembly for an electric iron 55 having a base plate, a pressure plate and a heating element, said assembly comprising thermostatic members for controlling the operation of the heating element, a bracket for supporting the thermostatic members in close 60 proximity to the base plate of the iron so as to receive heat mainly therefrom, a plate seated upon the top surface of the pressure plate of the iron, common securing means for clamping the base plate, heating element, 65 pressure plate and plate aforesaid together,

means carried by said latter plate for securing the same to the bracket to form a unitary construction therewith, and means for electrically connecting the heating element and the switch to a source of electrical energy 75 including terminal members secured to the latter plate.

In testimony whereof we affix our signatures.

FRANK KUHN.
